UNITED STATES PATENT OFFICE.

HENRY O. FLETCHER, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

SEWING MACHINE.

Application filed November 21, 1919. Serial No. 339,637.

To all whom it may concern:

Be it known that I, HENRY O. FLETCHER, a citizen of the United States, residing at Bridgeport, in the county of Fairfield and State of Connecticut, have invented certain new and useful Improvements in Sewing Machines, of which the following is a specification, reference being had therein to the accompanying drawings.

10 This invention relates to sewing machines being more particularly designed for lock stitch outsole or rapid stitchers for sewing shoes, and provides for improvements in the various sewing instrumentalities and combinations of such instrumentalities with each other in novel relationships to produce superior results.

20 A novel awl actuating mechanism is provided, the awl being driven by a cam on the main cam shaft, the operating connections for giving the piercing and retracting movement to the awl including improved means for allowing for the feed motion which is produced by a different cam path on the same cam disc.

25 Means is also provided by which the feed may be varied from a point convenient to the operator, this means requiring but slight movement to produce the desired adjustment, thus making it unnecessary for the operator to remove his hand from the shoe for any considerable time during the stitching operation.

30 It is also desirable to provide for initially positioning the awl with respect to the needle and other stitch forming instrumentalities in setting up the machine or for inserting a new awl or needle, and the present invention provides means whereby the initial position of the awl may be very accurately adjusted and in a very simple and expeditious manner.

35 The present invention provides also for positively pulling off the thread from the wax pot whereby the thread measurer is released from this duty. This construction causes the tension of the thread pulled off by the thread measurer to be controlled entirely by the tension device without superposing thereon as has heretofore been the case, tension due to the wax stripper gland of the wax pot which is of variable amount being modified by frequent settings by the operator according to the condition of the thread and wax. This enables the tension to

be held uniform regardless of variations in the adjustments of any part beside the tension device.

A looper mechanism deriving its entire motion from a single double throw cam 60 groove is also provided, the looper being caused to lay the loop in the thread finger and the barb of the needle and thereafter to take a position with its eye in line with the thread as it is drawn up by the needle 65 and shuttle hook and thereafter pulled down by the take-up, to prevent reeving of the thread thereover. The looper mechanism is readily removable and when in position is counterbalanced to hold it in position and to 70 reduce wear between the cam and its follower.

A novel means of driving the shuttle is provided together with improved means for insuring the engagement of the shuttle hook 75 with the loop and the removal of the latter from the needle. This latter means entirely removes the loop from the needle in spread condition and thereafter moves the loop bodily out of the path of the needle and into 80 the path of the shuttle hook, thus insuring positive and certain action. A resilient element in the shuttle drive also provides against any sudden jerking on the thread as the shuttle hook engages the loop. The 85 shuttle and drive mechanism, together with the thread transfer for removing the loop from the needle and presenting it to the shuttle, are held in cooperative relation by a casing and may be assembled and disassembled as a unit with relation to other parts 90 of the machine.

Improvements also reside in the presser foot, the take-up, and the thread lock. A novel thread measurer is also provided, which 95 has provision by which the position of the locking of the upper and lower threads in the work may be adjusted, and which also measures off thread in accordance with the thickness of the work being sewed.

100 Another novel feature of the invention comprises a stop motion by which the sewing instrumentalities are arrested at a determined point in their cycle of operations, and thereafter the presser foot is raised and the thread lock opened by power to facilitate removal of the work from the machine.

105 A selective sliding gear transmission is also provided which may be interposed in the machine drive at will and by which its 110

speed is reduced to any one of a plurality of speeds each lower than the normal speed to facilitate sewing about the toe of a shoe.

A preliminary depression of a treadle serves to start the machine at its normal high speed and a further depression of the treadle throws in the transmission to reduce the speed.

Further objects and advantageous details and combinations of parts will appear from a description of one embodiment of the invention illustrated in the accompanying drawings in which,—

Fig. 1 is a front elevation partly in section of the upper portion of the machine;

Fig. 2 is a top plan thereof;

Fig. 37 is a cross section on line 37—37 of Fig. 33;

Fig. 38 is an end elevation of the stop mechanism;

Fig. 39 is a partial cross section on the line 39—39 of Fig. 2;

Fig. 40 is a side elevation of the portion of the stop mechanism showing near the left end of Fig. 33;

Fig. 41 is a disassembled perspective of the parts shown in Fig. 40;

Figs. 42 and 43 are perspectives of mating clutch elements shown in the right hand portion of Fig. 33;

Fig. 44 is a front elevation of the lower portion of the machine;

Fig. 45 is a left side elevation of the same portion, parts being broken away;

Fig. 46 is a longitudinal cross section through the speed-reducing mechanism on line 46—46 of Fig. 48;

Fig. 47 is a detail of a cam mechanism;

Fig. 48 is a horizontal section through the machine base showing some of the drive mechanism in plan;

Fig. 49 is a cross section through the speed-reducing mechanism along the line 49—49 of Fig. 46; and

Fig. 50 is a cross section along the line 50—50 of Fig. 46.

Needle and awl motion.

Z indicates the usual machine head having a cam shaft S mounted for rotation therein and suitably driven and having the usual hand wheel D on one end. This cam shaft has fixed thereon a series of cam discs A, B and C. Extending at the right hand side of the machine head is a bracket member F. Within this bracket member is mounted a slide H adapted for movement transversely of the machine, said slide having at its left extremity an upwardly extending post T. Extending from the head Z is a bracket K, said bracket K and the post T having their free extremities provided with aligned openings in which are mounted oppositely directed studs W and X, respectively (see Figs. 5 and 6). Upon the stud W is mounted the needle sector 4 carrying a hook needle P of the usual form and also serving as a support for the needle guide P². Upon the stud X is pivotally mounted the awl sector 7 carrying the awl O. The stud X is hollow and provides a guide opening for a pin W' 130

projecting from the stud W whereby the awl and needle sector are kept in proper alignment at all times, the parts being so arranged as to permit longitudinal movement 5 of the awl sector for feeding the work. Disc B is supplied with a face cam groove in which engages a cam roll 1 which is carried by an oscillating lever 2, the latter being supported for rocking movement on a shaft 10 328 on the machine frame. The free extremity of the lever 2 is pivotally connected through a link 3 to an arm formed on the needle sector 4 whereby rotation of the cam disc serves to actuate the needle. Cam disc 15 C has formed therein a face cam groove in which is a roll 5 carried by a lever 6 also rockable on the shaft 328. The awl sector 7 has a rearwardly extending arm 8, the extremity of said arm being in substantial vertical alignment with the free extremity of the lever 6, said free extremity of lever 6 being forked to provide spaced apart ears 9, 9^a, said ears being provided with aligned openings in which is mounted a stud screw 10, one end of which has screw threaded engagement with the opening in the ear 9. Freely rotatable on the stud 10 is a sleeve 11, the extremities of which abut against the inner surfaces of the ears 9, 9^a, respectively, 20 said sleeve having projecting from diametrically opposite sides a pair of pivot studs 12, 12^a. 13 is a short link having its end 14 enlarged and provided with a central opening 15, said opening being of a diameter slightly 25 greater than that of the sleeve 11. Enlargement 14 is provided upon one face with a bearing surface 16 terminating in a shoulder 17 and against said bearing surface and shoulder is arranged to be positioned a cover 30 plate 18, screws 19 being provided for securing said plate in fixed relation against the enlargement portion 14 of the link. The mating surfaces of the parts 14 and 18 are provided with complementary semi-circular 35 openings, which, when the plate 18 is in proper position, provide journal openings for the pivot studs 12, 12^a. The opposite faces of the parts 14 and 18 are cut or beveled away as indicated at 20, 21, respectively, whereby to permit the link 13 to rock lengthwise of stud 10 by reason of the arrangement of the pivots 12, 12^a carried by sleeve 11 on said stud. The opposite end of the link 13 is provided with an enlarged 40 extremity 14' having a bearing surface 16' and a shoulder 17' against which is secured a cover plate 18', the parts being similar to those already described. The parts 14' and 18' are provided with complementary openings forming journals wherein are pivotally supported bearing studs 12' and 12^a' carried upon a sleeve 11' which in turn is mounted for rocking movement on a headed stud 10' fixed within the extremity of the 45 arm 8 carried by the awl sector, the de-

scribed connections of the link to lever 6 and arm 8 thus constituting universal joints.

Cam disc C has a peripheral cam groove 31 (see Fig. 2) with which engages a roll 39 carried upon a lever 38 pivoted to the machine frame at 37, the lower extremity of this lever being provided with a curved slot 41. Within the slot 41 is mounted a block 42 carried upon the extremity of a lever 43, said lever being pivoted at 44 upon the upper end of link 45. The link 45 is pivoted at its lower end upon a stud 46, said stud extending through aligned openings in a pair of spaced apart plates 47 attached by means of screws, or other suitable devices, to a pair of posts 49, 50 upstanding from the slide H (see Figs. 1 and 4). The posts 49, 50 are provided with openings in which are mounted a pair of set screws 49^a, 50^a, respectively, the extremities of said screws being arranged to bear against the link 45 at opposite sides thereof, opposite stud 44, whereby to adjust the angular position of the link 45 about its pivot 46. Adjacent the lower extremity of the lever 38 is a thin plate or fin 51 extending outwardly from the post T, said plate being provided with a series of openings 52, for the reception of a pair of pins 53, 53^a, said pins passing through the plate and extending into the path of the end of lever 43 adjacent block 42. By means of said pins the limits of movements of block within the slot 41, may be adjustably fixed.

54 is a friction plate arranged to bear against a curved surface 51^a provided upon the edge of plate 51, said members 54 being supported upon the end of a slide rod 55, carried within an opening 56 in the lever 43, spring 57 serving to press the member 54 against the surface 51^a, the curvature of the latter surface, as well as of the slot 41, being formed with the stud 44 as a center.

Awl mechanism operation.

By reason of the above arrangement of parts, it will be clear that on rotation of cam disc C the rocking movement produced by cam roll 5 on the lever 6 in a vertical plan will be transmitted through the link 13 to the awl sector 7 whereby the awl will have imparted to it the desired oscillation for penetrating and retracting from the work.

Rotation of the cam disc C will also rock the lever 38 and through the slot 41 block 42 and lever 43 will impart a sliding movement to the slide member H. As the member H carries the post T, upon which is mounted the awl sector, the latter will have imparted thereto a transverse movement sufficient to feed the work, the universal connections between the sector and the link 13, and also between the link 13 and the lever 6, permitting such movement to take place freely.

By adjustment of the lever 43, as by

means of handle 58, the amount of movement of the slide H may be varied at the will of the operator, the stud pins 53, 53^a serving to determine such variation of adjustment within fixed limits, and the friction member 54 serving to keep the lever 43 in its proper adjusted position. It should be noted that the feed finishes at the same point for all adjustments of feed length.

By manipulation of the set screws 49^a and 50^a, the position of the pivot 44 may be varied, whereby adjusting the position of the slide H, together with the awl sector relatively to the lever 38, this adjustment serving to take care of inaccuracies in the setting of the awl as well as for slight variations in the mechanism, due to wear.

The handle 58, carried by lever 43 is in a position to be easily manipulated by the operator, requiring merely an upward or downward blow to give the necessary change in adjustment of the feed length, thus requiring the operator to remove his hand from the work for only a short period.

Thread pull-off.

This mechanism is shown in detail in Figs. 4 and 32.

Extending rearwardly from the head Z is a bracket 60 which provides a bearing 61 for a thread tension roll 62. The bracket at 60 provides a guide 63 in which travels a roller 64, carried upon a pin 65 fixed in the lower end of a link 66. The upper end of link 66 is pivoted at 67 to the forked extremity 68 of a rearward extension 6² of the awl operating lever 6. 70 is a stud fixed near the lower end of link 66 and provides a bearing for a thread guide roller 71. 72 is a secondary bracket extending from the guide 63 and has fixed therein a pin 73, having rotatable thereon a thread engaging roll 74. As shown in Fig. 32, the thread passes from the wax pot E over roll 74, under roll 71 and around tension roll 62, thence through the thread lock, the thread measurer and the take-up.

The operation of the thread pull-off is as follows: In the operation of the machine the link 66 will be moved downwardly, as the awl is retracted from the work, and as the thread is held in the thread clamp at this time, roll 71 in passing down the guide 63 and between tension roll 62 and guide roll 74 will serve to draw the thread from the supply. Upon opening of the thread clamp the thread measurer is now enabled to secure slack thread already pulled from the supply, thus releasing the thread measurer from the duty of pulling thread through the wax pot and stripper.

Looper mechanism.

This mechanism is shown in detail in Figs. 20 to 23, inclusive.

As constructed the looper lever 100 carries at its outer end an angular looper arm 101, which has at its upper end an offset thread eye 102. Lever 100 is provided at its opposite end with a ball 103, adapted to engage in a double throw cam groove 104 of substantially circular cross section in cam disc B. Lever 100 is guided to move in a plane by means of guides 106 and 106^a supported by the frame F of the machine, lever 100 being provided with an enlarged portion forming a slide 107 engaging between the guides. A double-forked link 108 carried by pin 109 is pivoted to lever 100 at 110, the fork jaws engaging on either side thereof. The ball 103 can move transversely to the axis of shaft S by means of the pivotal mounting of the link 108, and it is also capable of movement axially of shaft S by reason of the pivotal mounting at 110. As shown in Fig. 3 the cam groove 104 varies in the direction of the axis of shaft S, and as shown in Fig. 20 also varies radially therefrom, whereupon both movements are imparted to ball 103 by a single cam. Cam groove has a lateral opening 104' (Fig. 20) for insertion and removal of the ball 103, and pin 109 carries a coil spring 109' acting to raise link 108 to hold the ball in place, and to relieve the walls of the cam groove 95 from its weight.

The operation of the looper mechanism is as follows: The cam groove 104 is so cut as to time the operation of the looper with relation to the needle, in the following manner:—As the awl pierces the work the looper moves to the position shown in Fig. 22 in a single plane away from the needle path, at which time the usual thread finger 111 is positioned to receive the thread. As the needle descends the looper follows the path shown substantially in the arc of a circle around the needle about 270° or three-fourths of a revolution. This motion serves to lay the thread in the thread finger 111 which then draws back and in the barb of the needle as shown in Fig. 23. The needle then begins to retract through the work, carrying the loop of thread with it, the thread finger moving forward to deliver thread thereto, and as soon as the needle is out of the way the looper moves by an almost radial path to the center of the arc it has been describing, to a position directly under the hole in the work through which the needle has passed. As the needle further retracts, it is therefore seen that the thread is pulled up in a straight path through the hole in the work, and through the eye of the looper. The looper remains substantially in this position during the taking of the loop from the barb of the needle and the taking thereof by the shuttle hook, the passing of the loop around the shuttle and the action of the take-up in drawing down the loop through 120 125 130

the work to set the stitch. The parts are then ready for a repetition of the same cycle. This looper path, substantially the periphery of a sector of a circle, allows the looper to lay the thread in the needle hook and then move in line with the retracting needle by a small movement.

Thread finger mechanism.

10 The thread finger 111 is mounted to slide forwardly and rearwardly in the machine frame. As shown in Fig. 1 a rock arm 112 fast to a rock shaft 113 carried in the forward part of the machine, is pivoted at its upper end by a sliding pivoted joint of any suitable description to the rear end of finger 111. A rock arm 114, also fast to rock shaft 113, has pivoted thereto a link 115. A link 116 is pivoted at one end to link 115 the pivot carrying a cam roll 117 projecting into an outer cam groove 118 in the left face of cam B. The other end of link 116 is journaled on a rock shaft 328 additional functions of which will be later described.

25 *Thread finger operation.*—The looper having laid the thread in the thread finger in the position shown in Fig. 22, the thread finger is caused to retract by cam B and the connections described drawing thread from the looper until the looper has laid the thread in the barb of the needle as shown in Fig. 23. As the needle retracts, the thread finger moves forward again to keep the thread in place on the needle without being pulled thereover, until after the needle barb has entered the work whereupon the thread slips off the thread finger. This thread finger operates in the usual manner and therefore has not been shown in detail in this application.

Shuttle drive and thread transfer mechanism.

45 This mechanism is shown in detail in Figs. 10 to 14.

The main driving cam shaft S of the sewing machine carries thereon a beveled gear 200. Perpendicular to shaft S is a shuttle drive shaft 201 journaled in a bracket supported at one end on the main frame of the machine and at the other by suitable journals on shaft S. Shaft 201 carries a beveled gear 202 meshing with gear 200, these gears being of such size as to drive shaft 201 three times to one rotation of shaft S. Shaft 201 carries a gear 203 thereon meshing with gear 204, carried by a stub shaft 205 mounted within a casing carried by the shuttle drive shaft bracket. As shown in Fig. 14, shaft 201 carries at its forward end a collar 206 made fast thereon by means of a pin 207 and has a projection 208 which serves as one part of a driving connection for the shuttle. The other part of this driving connection 60 consists of a plate 209, provided with an

offset 210. Offset 210 is in the form of a hollow open-ended socket and carries therein a coil spring 211, the lower end of which is seated in the base of offset 210 against an adjustable screw plug 210', and its upper end projects somewhat from the top face of part 210.

70 Plate 209 carries also an abutment 212, spaced from the offset 210 so that the projection 208 of collar 206 may come therebetween, engaging the abutment 212 on one side and the upper end of coil spring 211 on the other. Plate 209 also has a portion 213, whose side face is in the same plane as abutment 212 and offset 210, so that they may receive a cover plate 214 which is bolted thereto, and which retains collar 206 in proper position with projection 208 between abutment 212 and spring 211.

75 A space 215, and opposite thereto a similar space 215^a is left between the abutments 212 and projection 210 and portion 213, so that access may be had to the pin 207 for the purpose of assembling and disassembling the driving elements.

80 Plate 209 carries on its outer face two driving lugs 216 and 217 which are adapted to engage within the opening of the loop taking hook 218 of the shuttle 219. Lug 216 engages the shuttle at the opposite end of the opening from the hook at which time lug 217, which is near the point of the hook, is out of contact therewith, the shuttle opening being somewhat longer than the distance over the lugs to allow the thread to pass 95 around the shuttle between the shuttle and the lugs 217 and 216 in turn. Shuttle 219 is mounted for rotation in a portion of the machine frame, as shown in Fig. 10, by means of a tongue carried by the shuttle, and working within a circular groove in said frame, the frame being open for about one-fifth of the circumference, and, as shown in Fig. 1, the bobbin is eccentrically carried within the shuttle so that it is bodily rotated by the rotation of the shuttle.

100 Mounted on stub shaft 205 is a cam 220 which rotates with the gear 204 and may be integral therewith if desired. Cam 220 has a cam groove 221 cut therein. Mounted to oscillate and slide in the frame is a shaft 222. At its forward end, shaft 222 is bent downwardly and carries at its lower end an upwardly turned double thread-transfer hook 223. Fixed to the shaft 222 are collar members 224 and 224^a between which is mounted a roller-carrying member 225, having a roller 226 at its outer end engaging within cam groove 221. Loosely carried on shaft 222 is another collar 227, having an arm 115 projecting therefrom and carrying at its outer end a roller 229, engaging a cam groove 229' cut in the face of gear 204. Arm 228 carries an outwardly projecting finger 228' which projects between the jaws 230 and 230^a 120

of a collar member 231 fixed on shaft 222. Adjusting screws 233 and 233^a having lock nuts thereon, are carried by the jaws 230 and 230^a so that the angular relation of arm 228 to fork members 230 and 230^a may be adjusted. Collar 227 is also provided with an annular groove 234 which is engaged by a forked bracket 235 rigidly carried by the casing which encloses gear 204 and cam 220. It should be noted that the shuttle and thread transfer mechanisms are held in assembled relation by the casing in which they are mounted and may be assembled and disassembled as a unit with relation to other parts of the machine.

Shuttle drive and thread transfer operation.—Rotation of the main cam shaft S drives the shuttle actuating shaft 201 at three times its speed. Shaft 201, by means of projection 208 engaging spring 211 imparts a resilient rotating movement to the plate 209, and the lugs 216 and 217 engaging within the hook of the shuttle serve to rotate the latter at three times the rate of the main shaft. At the same time gear 204, which is three times the size of gear 203, is driven at the same rate as the main shaft S. The transfer hook 223, is adapted to be positioned in the path of motion of the curved hook needle P and also to be moved out of said path and into the plane of rotation of the shuttle 219 to remove the loop of thread from the barb of the needle and transfer it into the plane of rotation of the shuttle, so that it may be engaged by the shuttle hook. Shaft 222 carrying transfer hook 223 is moved axially by means of the cam roller 226 lying within the cam groove 221 of cam 220 and is rocked at suitable times by cam roller 229 engaging groove 229' in gear 204 and acting on collar 231 by means of finger 228' engaging between the forks 230 and 230^a.

The cycle of operations will now be clear from an inspection of Figures 15 to 19 on Sheet 4 of the drawings. As shown in Fig. 15 the loop of thread has been drawn up through the work by the needle. At this time hook 223 is in the position shown in solid lines. The hook is then rocked upwardly into the needle path at one side of the loop of thread. It is then moved axially so that one side of the loop is laid within it as shown in Figs. 16 and 17. A further motion in the same direction serves to draw the loop over into the path of the shuttle hook, the needle dipping to release the loop. The loop is then carried entirely by the hook 223 the hook elements of which are so spaced apart that the shuttle hook may pass therebetween as shown in Figs. 18 and 19, which insures that it will properly engage the loop. As the shuttle hook engages the loop the resilient drive allows it to yield slightly and so avoids a sudden jerk as the loop begins to pay out to pass around the bobbin. Further rotation of the shuttle draws up the loop from the work, and off the transfer hook 223, and throws the loop of thread over the bobbin eccentrically carried within the shuttle. The loop of thread carried by the shuttle hook passes around the shuttle casing and in turn between it and lugs 217 and 216 of the driving mechanism, thus passing entirely around the shuttle, the take-up to be described later operating to pull the loop down over the shuttle and into the work to set the stitch. The shuttle hook having taken the loop from the transfer hook 223, the latter goes back to its former position so that it will not interfere with the down stroke of the needle or other moving parts during the two rotations of the shuttle before the next loop drawing movement of the needle.

Presser foot mechanism.

This mechanism is shown in detail in Figs. 24 to 29, inclusive.

Parallel with and forward of the main shaft S is a shaft 300 carried by fixed bearings in the machine frame. Loosely carried on shaft 300 is a sleeve member 301, provided integrally therewith with a rearwardly extending arm 302, a downwardly extending arm 303, the latter arm being for a purpose which will later be described, and a forwardly extending arm 304. At its forward end arm 304 carries a suitable presser foot 305. At its rear end arm 302 has pivotally connected therewith at 302' a cylindrical rod 306. At its lower end, rod 306 extends slidably through a sleeve 307, having a bifurcated forwardly extending top portion 308. The rear portion of sleeve 307 is cut away as at 309, and rod 306 is likewise cut away at 310. Sleeve 307 is slidably mounted in a guide sleeve 311, which carries an outstanding stud 311', by which it is pivotally mounted on the machine frame. Sleeve 311 also carries a double pawl 312, normally spring-pressed into engagement with teeth formed on the cut-away portion of rod 306. Sleeve 311 is also provided with a pivotally mounted bracket 313, slidably supporting a rod 314 which extends upwardly in substantially parallel relation to rod 306. Rods 306 and 314 are held in position at their upper ends by means of an L-shaped bracket 306', slidably sleeved on rod 314, and engaging the pivot 302' at the upper end of rod 306. Nuts 306^a are attached to the top of rod 314 and are normally spaced from bracket 306' forming a lost motion connection between rods 306 and 314. Beneath bracket 306', rod 314 is provided with an outstanding bracket member 315 rigidly mounted thereon.

Pivoted on arm 304 at 304' is a finger lever 316 normally urged forwardly and

downwardly by a coil spring 316'. A link 317 is pivoted at 318 on finger lever 316, and its other end is pivotally connected at 319 with a link 320, pivoted at its rear end on pivot 302'. On raising lever 316, link 320 is adapted to contact with outstanding bracket member 315, and to depress the same, carrying the rod 314 therewith. Arm 304 carries an abutment 321, and finger lever 316 has a corresponding abutment 321', arranged to contact therewith when the finger lever 316 is thrown up and back against the tension of spring 316'. Rod 314 is provided with a pin 322 over which the double-forked end of arm 323 engages. This arm is rigidly attached to a rod 324, slidably mounted in a bearing 325, carried by the frame of the machine. An abutment 326 is adjustably fixed on rod 324, and a coil spring 327 is placed between the abutment and bearing 325 to hold the abutment normally at its upper limit of travel. Abutment 326 has a cut-away portion 326' at its lower end, which, on depression thereof engages the rear ends of pawls 312 to release them from engagement with the toothed portion of rod 306.

The shaft 328 is carried by the machine frame, below the main cam shaft S. Arm 329 is fixed on this shaft to the right of the cam C which, as before described, actuates the awl and thread pull-off, and which has a cam groove 331 in its side face engaging a roll 332 carried at the end of arm 329. On the other side of cam C is an arm 333 rigidly carried on shaft 328 to turn therewith. Arm 333 is provided with a forked extremity 334, within which sleeve 307 is located. A pin 335 passing across this slot engages between the jaws of the fork extension 308. A screw 337 is adjustably positioned in arm 333 directly over the upper end of rod 324, and is arranged to contact therewith on a slight downward rocking of arm 333. A coil spring 307' surrounds rod 306 and bears at its upper end against the under side of a shoulder on rod 306 and at its lower end against the top of the member 307. Adjacent arm 333, and loosely fulcrumed on shaft 328, is a lever member 336 forked at one end as at 338, where it projects over the slotted portion of arm 323, and normally in contact therewith. The other arm of this lever has pivoted thereto a link 339 which in turn is pivoted to the end of arm 340, carried rigidly on a shaft 341 arranged parallel to cam shaft S. Shaft 341 is designed to be connected for rocking motion to a stop mechanism to be described.

The operation of the presser foot is as follows: During the feeding of the work it is necessary that the presser foot be released therefrom. This is accomplished by cam C which at the proper time rocks arm 329, depressing arm 333. This slides sleeve mem-

ber 307 on rod 306, relieving the compression of coil spring 307'. On further depression screw 337 contacts with the upper end of rod 324 and depresses it against the pressure of spring 327. This depresses abutment 326 in contact with the rear of the pawls 312 which are thereby rocked to release rod 306. Rod 306 is thus free to slide within the sleeve 307, and the presser foot 305 is thus free to be raised. On lever 329 being rocked back to its former position, spring 327 first moves abutment 326 out of contact with the pawls 312, which immediately spring back in engagement with rod 306, and prevent it from being depressed. Further upward motion of lever 329 serves to compress the coil spring 307', and rod 306 is allowed to play upwardly past the pawls as much as necessary to bring the presser foot down in contact with the work under the pressure exerted through the spring 307'. It is thus seen that the release of the presser foot for the feed motion of the work allows it to readjust itself at each stitch to varying thicknesses of work, and it is then clamped down with an unyielding pressure. Should it be desired to lift the presser foot by hand, this may be done at any time by raising the finger lever 316. Upon raising this lever, link 320 is depressed into contact with bracket 315. Lowering of bracket 315 causes rod 314 to slide downwardly, and pin 322 thereon, engaging arm 323, depresses rod 324 against the pressure of spring 327, by which action abutment 326 unlocks the presser foot, as previously described. On further movement of finger lever 316, abutment 322 contacts the abutment 321, and further motion of the finger lever is thereby caused to swing presser foot lever 304 about shaft 300 raising the presser foot against the action of spring 307'.

After stopping the machine the presser foot is raised from the work in the following manner:—Shaft 341 is rocked by the stop mechanism to be later described whereupon, through arm 340, link 339 and lever 336, the forked portion 338 engages the head of arm 323, and depresses the same against the action of the spring 327 and releases the pawls, as heretofore described. Further motion downward of rod 314 brings the nuts 306' to bear against the bracket 306' sleeved on the rod, which, acting on pivot 302' draws rod 306 downwardly thereby raising the presser foot from the work. By a similar action the presser foot might be raised as well as unlocked during the feed, if desired, by properly adjusting the movement of the parts.

125

Take-up mechanism.

This mechanism is shown in detail in Figs. 31 and 32.

Journalized in the forward lower part of 130

the machine frame is a rock shaft 400. This shaft carries a rocker arm 401, pivoted to a link 402 which in turn is pivoted at its upper end to lever 404 mounted to rock on shaft 328. This pivot between link 402 and lever 404 carries a cam roll 403, engaging in a cam path 403' in cam disc A at the left end of the machine. Shaft 400 also carries, loosely, a lever 405, having at its opposite ends thread rollers 406 and 407. Adjacent roller 406, lever 405 is provided with an abutment 408. Carried by a standard 409 on the frame of the machine is a vertically adjustable screw 410 the top of which may contact with abutment 408. Near the roll 407, lever 405 has an abutment 411. A standard 412 below abutment 411 carries an adjustable screw 413, and a coil spring 413' is mounted thereon, the upper end of which spring contacts with abutment 411, the lower end being supported by an enlarged adjusting portion of said screw. A double take-up lever 414 having thread rolls 415, 416 at opposite ends, is fixed to shaft 400.

The operation of the take-up is as follows: In operation, link 402 is depressed, rocking arm 401, which in turn actuates the take-up lever 414, lowering the front end and raising the rear end. The thread passes from the thread measurer roll 605 over the roll 416 at the rear end of the take-up lever, down under the roll 406, forward over the roll 407 and under the roll 415 at the forward end of the take-up lever. It is, therefore, seen that by rocking the take-up lever which is effected by cam A through members 403, 402, 401 and rock shaft 400, the take-up action is produced.

By adjustment of screw 413 the amount of thread pulled may be regulated and if desired the position of the locking of the threads in the work may be varied by this means. By lowering the screw less thread is taken up leaving the lock near the upper surface of the work. By raising the screw the lock is moved nearer the lower surface of the work. Rear stud 410 acts to prevent undue upward movement of the forward end of the take-up, while the spring 413' serves to relieve sudden jerks on the thread, and compensates for any slackness of thread or variations of thread tension as the various adjustments are made.

Thread lock.

This mechanism is shown in detail in Figs. 30, 31 and 32.

Loosely mounted on shaft 328 is a bell crank lever 500, the upper end of which carries a roll 501 arranged to be moved at suitable times by an inner cam path 500' in the left hand face of cam B (Fig. 1). The lower arm of bell crank lever 500 is pivoted to a link 503, which in turn is pivoted to a link 504 at 504'. An arm 505 is fixed

to shaft 506 carried at the lower rear portion of the machine head, and at its end arm 505 carries a thread locking shoe 508 which engages with a suitable stationary straight grooved thread guideway 509. A bell crank lever 510 is fulcrumed on shaft 506 and its lower arm 510' is pivoted at 507 to the lower end of link 504. A collar 512 is fixed on shaft 506 adjacent bell crank 510 and carries a bent arm 513 arranged to overlap the reversely bent arm 514 of bell crank 510. Suitable adjusting screws 515, 516 serve to fasten the bent arms 513, 514, together and furnish means by which the angular position of bell crank lever 510 on shaft 506 may be adjustably fixed, which serves to adjust the limits of motion of the shoe 508. A link 511 connects the joint of the toggle formed by links 503 and 504 to crank arm 517 (see Fig. 3) fast to rock shaft 341.

The operation of the thread lock is as follows: The thread passes through a perforation in arm 505 and into the groove of guide 509 and is locked at times between the locking shoe 508 and the guide 509. It must be unlocked at suitable times to allow the thread to be drawn forward by the thread measurer which will be described later. This is accomplished by means of the cam path 500' coacting with the cam roller 501, which rocks arm 500, pulling upwardly on the links 503 and 504, which normally are in alignment with each other or straight as shown in Fig. 31. This serves to rock the bell crank 510, shaft 506 and arm 505 which raises the shoe 508.

On stopping the machine it is desirable that the thread should be unlocked so that the thread may be drawn through when the work is removed from the machine. For this purpose the arm 517 is connected with rock shaft 341 which is actuated by the stop mechanism to be later described. By means of the link connection 511 acting on the joint 504' between links 503 and 504 this joint is pulled to the right (see Figs. 31 and 32) thereby breaking the toggle formed by these links, and rocking link 504 upwardly, which serves to rock lever 510 and raise the shoe 508.

Thread measurer.

This mechanism is shown in detail in Figs. 30, 31 and 32.

Pivoted to the rearward extension 6² of the awl operating lever is a depending link 602. Near its upper end, link 602 is adjustably, pivotally connected through rod 603 with the lower end of link 303 of the presser foot mechanism. The adjustment is effected by providing the rod 603 with a slot in which the pivot may be adjustably fixed by screw 603'.

Pivoted at 609' on the bracket 609 of the

machine frame is a rock lever 604, the forward end of which is provided with a thread roll 605. The rear end has an arcuate slot 606 and a pin 607, carried by the lower end 5 of lever 602, is arranged to play back and forth in this slot. A thread roll 608 is mounted on bracket 609 between the thread lock and the thread roll 605.

The operation of the thread measurer is as 10 follows: The thread measurer serves to draw off thread intermittently, measuring off enough for each stitch. For this purpose the thread after passing through the thread lock, passes over the fixed roll 608, and under the roll 605, carried by the lever 604. It is seen that by rocking roll 605 downwardly a length of thread will be pulled off between this roll and the fixed roll 608 and also between roll 416 on take-up lever 414 15 and the roll 605. This is accomplished by the rocking of lever arm 62 which has already been described in connection with the thread pull-off mechanism. On movement of arm 62 upwardly carrying with it link 20 602, the lower end of link 602 engaging lever 604 in the slot 606 serves to rock lever 604, thus depressing the thread roll 605.

To allow for different thickness of work the rod 603 is connected to the arm 303 of 30 the presser foot at one end, and at the other is pivoted to link 602. As the presser foot is raised, as by the increasing thickness of work, rod 603 will be pulled to the left, so that the lower end of link 602 will engage 35 slot 606 close to the fulcrum of the lever 604.

A uniform motion imparted to link 602 will, therefore, produce a greater throw of the thread roll 605, and thus pull off more thread. Upon depression of the presser 40 foot, due to work of less thickness passing therunder, rod 603 will be pushed to the right, carrying the lower end of link 602 further from the fulcrum of lever 604, thus serving to decrease the throw of the thread 45 roll 605, and so decrease the amount of thread pulled-off. By adjustment of the pivotal connection within the slotted end of rod 603 the amount of thread pulled off for any thickness of work may be adjusted 50 which provides means for adjusting the position of the lock of upper and lower threads in the work.

Stop motion.

55 This mechanism is shown in detail in Figs. 33 to 43.

700 represents a sleeve which is made fast in the main frame of the machine, and has journaled axially therein the main drive 60 shaft S. On its outer face this sleeve is provided with an enlarged boss 701 having a clutch face 702 at the outer end thereof, which is counter-bored as shown at 703 to receive the inner end of a sleeve 704 keyed 65 to the shaft S. This sleeve has a flange

705 which is offset adjacent its circumference forming the shouldered portion 706. A ring 707 is seated within a depression in the shoulder 706 and extends parallel to the outer portion of the flange 705 being spaced 70 therefrom to enclose an expanding brake band 708 (see Fig. 37) pivoted at one end at 708' therebetween. The other end of this brake band rests against the flat portion 709 in a stub shaft or pin 710, which is also journaled in the ring 707 and flange 705. Adjacent the flange 705 is fixed a yoke 711 on pin 710 and on the opposite side from flange 705 pin 710 is provided with a second flat portion 712, facing in the opposite direction 80 from the flat portion 709. A second brake band 713 is carried by a pivot 714 in a ring member 715 which bears in an annular depression 716 in a sleeve 717 journaled on the boss 701 of the sleeve 700 and whose outer 85 portion is cup-shaped forming a flange 757 to enclose brake band 713. Ring 715 is carried to rotate with flange 705 by means of the pin 710 which finds bearing in a suitable opening therein. Rotatably carried on the 90 sleeve 704 is a second sleeve 718 (Figs. 33 and 42) which has a clutch face 719 adapted at suitable times to engage the clutch face 702 of the sleeve 700. A ring 720 having a perforated boss 721 extending therefrom is 95 rotatably carried by sleeve 718, a threaded washer 722 engaging the outer surface of the sleeve 718 to hold the ring 720 in position thereon. Sleeve 718 on its interior has an annular groove 723 and opening thereinto 100 are slots 724, 724a.

Sleeve 718 also carries a cam member 725 which coacts with a roller 726 carried by the yoke member 711. A coil spring 727 is engaged at one end in a perforation in the flange 705 and surrounding a portion of the sleeve 718 is seated at its other end in a similar perforation therein. This spring is under compression lengthwise and normally serves to slide the sleeve 718 toward the sleeve 700 to bring their respective clutch faces 719 and 702 in engagement. This spring also allows limited relative rotation of sleeve 718 on the sleeve 704. Pin 710 beyond the journal in the ring 707 has a reduced cylindrical portion 728 on which is rigidly carried a lever arm 729 (see Figs. 36 and 37). This lever arm has a hub 730 engaging over the portion 728; which hub has an annular groove 731 adjacent the ring 707 furnishing a sliding guideway for a wedge cam 732. A pin 733 carried by arm 729 engages a slot 734 in the sliding cam 732 and serves to slide the cam toward and from the portion 728 on rocking of the lever 729. As shown in Fig. 41, cam 732 is provided with a guideway 735 for supporting wings 736 and 736a carried on a ring member 737 journaled on the exterior of a sleeve 738 (Fig. 36). This sleeve forms part of a 130

drum 739 having an outer flange 740 projecting over and enclosing the ring 707, brake 708 and flange 705, as far as a portion of the yoke 711. This sleeve 738 is journaled on the exterior of the drive shaft S and abuts at its inner end against the fixed sleeve 704. Slide cam 732 has inclined cam portions 741 and 742 which engage against similar inclined portions 743, 744 on the rear face of the ring 737. By this means the sliding of the member 732 across the axis of the shaft S in one direction will serve to push ring 737 axially of the shaft therefrom. The outer face of ring 737 has inclined wedge cam members 745, 745^a and 745^b which, at suitable times, engage reversely positioned similar cam members 746, 746^a and 746^b carried by a similar ring member 747 slidably mounted on the sleeve 738 (see Fig. 40). A spring 748 formed as a corrugated ring is seated between the rings 737 and 747 to normally urge these members apart. Ring 747 has engaging therein pins 749, 749^a and 749^b which project from its outer side through perforations on the rear face of the drum 739 into suitable sockets in a ring 750 which bears against a thrust ball bearing 751 seated within the hub of a belt pulley 752. Pulley 752 has an annular flange 753 thereon which at times may project over the outer end of the drum 739 and have frictional engagement therewith by means of complementary bevel surfaces on the flange and drum. The yoke member 711 before referred to is provided with a curved slot 754 so that it may swing about the axis of pin 710 across the sleeve 718 without contact therewith. At a point on the opposite side of the roll 726 it is provided with a roll 755 which at times rides into an enlargement 756 formed on the inner surface of the flange 740 of drum 739. The yoke member also has a depression 758 constructed to house a coil spring 759 seated at one end against the yoke member and at its other end against an abutment 760 carried by flange member 705. This spring normally urges the yoke member to its further limit of travel away from the abutment 760. A pin 761 (see Figs. 35, 36 and 37) is made fast at one end in the perforation of the lug 721 carried by ring 720 and projects through an opening in flange 705 and a similar opening in ring 707 and is provided at its end with a bevel portion 762. Pivoted at the outer end of lever 729 is a cam lever 764 which is urged inwardly toward the main shaft and against the beveled portion 762 of pin 761 by means of a leaf spring 765 fast at one end to a portion of the lever 729 and bearing at its free end near the extremity of the cam lever 764. Cam member 764 carries at its outer end a beveled cam incline 767 to contact with portion 762. On the outer lateral face of cam lever 764 is an

outstanding abutment 768 which when the cam lever 764 is swung outwardly about its pivot may contact with a roll 769 carried by the drum 739. On its outer lateral face also lever 729 carries an abutment 770 (Figs. 70 36 and 37) which may contact at certain times with an abutment 771 carried by the drum 739. The shaft S is shown as hollow and extending therein is a sliding rod 772. At its inner end rod 772 is perforated to receive a square bar 773 the outer ends of which project through axial slots 774 in shaft S and sleeve 704 into the annular groove 723 of sleeve 718 (Fig. 42) so that by axial movement of rod 772 sleeve 718 80 may be moved longitudinally of the sleeve 704. The openings 724 and 724^a are formed in the sleeve 718 to facilitate the assembling of the parts and perform no function during operation of the mechanism. On the outer 85 end of rod 772 is carried a flanged collar 775 fast thereto and a disc 776 placed against the end thereof serves to rotatably hold in position a ring 777, the members 775 and 776 being held in position by a suitable 90 shoulder on rod 772 and a nut 778 screwed on the reduced extremity thereof.

Journalled on a bracket 779 fast to the main frame of the machine (see Figs. 1 and 3), is a three-armed lever 780 the inwardly extending arm 781 thereof being pivotally connected to a rod 782 which may be actuated by a treadle as will be later described. An upwardly extending arm 783 is pivoted to a laterally extending arm 784 which at its outer end is pivoted to a lever 785 journalled at 786 to bracket 779 on the main frame of the machine. At its upper end lever 785 is bifurcated, the forks extending either side of the ring 777 to 105 which they are pivoted by studs 787, 787^a. Rigidly carried at the outer end of shaft S is a cam 788 having a high portion 788^a (see Fig. 38) and a substantially radial low portion extending from adjacent thereto to the point 788^b. A latch member 789 (see Fig. 1) is slidably carried near the upper end of lever 785 and is normally urged upward by a coil spring 790 seated in a suitable depression in the lever. An adjustable abutment 791 is also carried by the lever and is arranged to take the side thrust exerted thereon by contact with the end face of the cam 788. Latch 789 in its normal outward position will not clear the high point of the cam 788 and when this part of the cam is downward, it is evident that the upper end of the lever 785 cannot be thrown inwardly. This action is permitted, however, when the low portion of cam 788 is toward the latch 789. A spring 792 bears against the cam 788 at one end and is seated within the hub 793 of the belt pulley 752 and bears against the same at its opposite end tending to push the 110 115 120 125 130

belt pulley into engagement with the drum 739. Lever 780 is provided with a third arm 794 (Figs. 1 and 38) which is pivoted by means of a ball joint to a connecting rod 795 which at its other end is pivoted in a similar manner to a rock arm 796 carried by a rock shaft 797 journaled in the machine frame. A toggle link 798 is also fast to the shaft 797 and carries at its outer end 5 a second toggle link 799. At its outer end link 799 carries a pin 800 riding within an angular slot 801 in a rock lever 802. This rock lever is carried by the shaft 341 which as above described is connected to 10 the presser foot and the thread lock mechanism. Toggle lever 799 also carries a roller 803 at its outer end and when the pin 800 is in the upper part of the angular slot 801 this roller is in the path of a cam 15 projection 804 carried on the outer face of the flange 740 of the drum 739. Extending from the exterior of the member 717 (Figs. 38 and 39) is a lug 805 carrying a 20 square pin 806. Adjacent thereto is a curved housing 807 carried by the frame of the machine and which is open midway on the side facing member 717. The ends of 25 this housing are tubular and threaded to receive the threaded plugs 808, 809 which 30 may be fixed in adjusted position therein by lock nuts 810 and 811. Midway, the housing is provided with inwardly extending lugs 812, 812^a. Coil springs 813, 814 are seated within the housing, their outer 35 ends bearing upon the abutments 808 and 809, respectively, and their inner ends bearing against discs 815, 816 which may slide within the housing and into contact with opposite sides of the abutments 812, 812^a. 40 The square pin 806 extends between the discs 815 and 816 and normally retains them out of engagement with the abutments 812 and 812^a. These springs tend to retain pin 806, and consequently member 717 yieldingly stationary with respect to sleeve 700. 45

The operation of the stop motion is as follows: Assuming the parts in position and the machine running, the rod 782 being depressed and holding the rod 784 to the sight as viewed in Fig. 1, the upper end of lever 785 is outward with the latch 789 out of the path of the cam 788 in the position shown in Fig. 38. In this position the drive member or belt wheel 752 is in frictional engagement with the actuating member consisting of the drum 739; the 50 brake band 708 is expanded against the inner surface of the flange 740 of drum 739 by means of the pressure of the flat face 709 of the pin 710 thereon; the cam lever 764 is in position for the lug 768 to engage the roll 769, which pushes therethrough on the pin 710 and drives, through this pin, the driven member comprising the flange 55 705 and the sleeve 704 which is keyed to the shaft S. The rod 772 is also rotating and driven by the ends of the bar 773 extending through the slot 774 in shaft S and in the sleeve 704. The clutch members 719 and 702 are out of engagement in 60 this position, and the brake band 713 is loose within the flange 757 of the substantially stationary member 717. It is thus seen that the entire mechanism carried on the shaft S is in rotation. When it is desired to stop the machine the operator allows the rod 782 to rise. If desired, a separate spring may be used to help this action, but the spring 727 may be sufficiently heavy of itself to cause this action. The raising 65 of rod 782 rocks the lever 780 moving rod 784 to the left as shown in Fig. 1 and rocking the upper end of lever 785 inwardly. When the cam 788 is in a suitable position for the latch member 789 to be passed 70 thereunder, the rod 772 is carried to the right, these parts thus being then in position as shown in Fig. 1. At the same time the lever arm 794 is rocked downwardly carrying the connecting rod 794 and rocking 75 the shaft 797 to straighten the toggle formed of rock arm 798 and member 799, thus pushing the pin 800 up into the upper end of the angular slot 801. By this means the roll 803 is moved upwardly. The movement of 80 rod 772 to the right, by engagement of the ends of the bar 774 within the annular groove 723 of sleeve 718 serves to push the same to the right so that the clutch face 719 thereon will be brought into engagement with the clutch face 703 carried by 85 sleeve 700. As sleeve 700 is fixed to the frame of the machine this will serve to stop the rotation of sleeve 718 when the clutching lugs come into contact, the other parts 90 continuing their rotation and the coil spring 727 yielding thereto. The cam member 725, rigidly fixed to the sleeve 718, is also stopped, whereupon the roll 726 carried by 95 the yoke member 711 rides up its outer face 100 and by rocking the yoke member 711 rocks the pin 710. The rocking of the pin 710 first turns the flat portion 709 out of contact with the end of the brake band 708 allowing the same to retract out of engagement 105 with the inner surface of the flange 740 of drum 739. The lateral motion of the sleeve 718 also withdraws the pin 761 sufficiently from the beveled cam face 767 of the cam arm 764 to allow the spring 765 to 110 throw this member inwardly toward the shaft to clear abutment 768 thereon from the roll 769. Further rocking of the pin 710, acting on the end of the brake band 713, expands this latter into engagement with the 115 inner surface of flange 757 of the member 717, thus coupling the shaft to member 717. By this means it is seen that the sleeve 718 120

fast to the shaft S has been uncoupled from the drum 739 by the loosening of the brake band 708 and the retraction of the cam lever 764 from contact with the roll 769. It is also to be noted that immediately after such disconnection the brake band 713 locks this mechanism to the member 717 which is resiliently held from rotation by means of the cushioning springs 813, 814, to take up the shock of the driven parts, thus stopping the rotation of the driven shaft. The drum 739 on the other hand is still connected frictionally to the drive wheel 752. The rocking of the pin 710, however, has served to move the pin 733 on lever 729 inwardly thus sliding the cam 732 across the axis of the shafts and moving the cam ring 737 outwardly against the action of the spring 748. The parts are so related during the rotation of the mechanism that the cam portions 745, 745^a, 745^b are opposite the spaces between the cam portions 746, 746^a, 746^b so as to pass between them on the sliding of ring 737. On further rotation of the drum 739 carrying ring 747 therewith, ring 737 being held from rotation by the stopping of shaft S, the bevel surfaces of these members are caused to ride over each other so forcing the ring 747 to the left, and by means of the pins 749, 749^a and 749^b pushing against the thrust bearing 750 the belt pulley 752 is pushed to the left out of frictional contact with the surface of the drum 739 into the position shown in Fig. 1. It is now seen that the pulley 752 is disconnected from the drum 739 a portion of the revolution after the main shaft has been disconnected and stopped. As this disconnection of the drive wheel and the drum takes place the lug 770 on the lever 729 contacts with the fixed lug 771 on the drum, thus positively stopping the drum 739 from further rotation by engaging it through lever 729 and pin 710 with parts locked to member 717. The parts are so timed that the cam projection 804 on the exterior of the drum 739 contacts with the roll 803 just after the main shaft has been disconnected and stopped and during the continued motion of the drum after this action, this cam portion or projection forces the roll 803 downwardly and the pin 800 rocks the arm 802 thereby rocking shaft 341 to release and raise the presser foot and open the thread lock in the manner already described. It is therefore seen that the first action of this stop motion is to stop the main shaft of the machine to stop the normal running of the machine, and thereafter by power the presser foot is raised and the thread lock is opened. When this is accomplished the power means is entirely disconnected.

When it is desired to start the machine

the operator depresses the rod 782, whereupon, by means of the lever 780, the cam roll 803 is pulled down out of the way of cam 804, the pin 800 riding in the angular slot 801, and the sliding rod 772 is pulled to the left as shown in Fig. 33. Rock shaft 341 is now free to turn, which it does by the action of the presser foot spring 307 to lower and lock the presser foot and by the straightening of the toggle formed by links 503, 504 to close the thread lock. The movement of the rod 772 pulls the sleeve 718 to the left and out of clutching contact with the fixed clutch member 702. This projects the pin 761 against the inclined cam portion 767 of the cam lever 764 and on slight relative rotation of the parts the cam lever is thrown outwardly. Spring 759 thereupon acts to throw the yoke member 711 as shown in Fig. 34, to the left but in this position of the parts the roll 755 contacts with the smaller diameter portion of the flange 740 preventing the completion of its motion. The action, however, is sufficient to release the brake band 713 so that the main shaft is free to be rotated, but not sufficient to expand the brake band 708. This motion is also sufficient to retract the sliding cam member 732 to allow the rings 737 and 747 to retract under the action of spring 792 so that the belt pulley 752 engages the drum 739. This starts the rotation of the drum member 739 and when the enlarged portion 756 of flange 740 comes opposite the roll 755 the yoke member is allowed to complete its motion and to effect the frictional clutching of the brake band 708 against the interior of the drum 739. The drum 739 is therefore now in frictional clutching engagement with the main shaft S through the brake 708 and the flange 705 and the fixed sleeve 704. When the roll 755 has reached the point within the surface 756, as shown in Fig. 34, the cam member 764 has approached the position shown in Fig. 36 with its lug 768 contacting with roll 769. At this point, therefore, there is positive driving engagement between the drum 739, the cam lever 764, lever 729, pin 110, flange 705 and sleeve 704 and the parts are in full driving position. It should be noted that the last stitch before stopping is entirely completed according to the normal running stitch-forming cycle with all parts in normal running position before the thread lock is opened and the presser foot raised and that the thread lock is closed and the presser foot is down and locked when the first stitch is started on starting the machine. This insures that all stitches shall be perfect and uniform from the first to the last, which is impossible

when the thread lock and presser foot are actuated during the formation of the first or last stitch, or both.

5 Drive and speed control mechanism.

This mechanism is shown in Figs. 44 to 50, inclusive.

On the rear of the machine standard Y is fastened a bracket 900 having at one 10 end thereof a bearing 901 for a horizontal shaft 902. A gear casing 903 is carried on the bracket 900, and one end thereof has a bearing 904 to support the other end of shaft 902. Within the gear casing 903 shaft 15 902 has fixed thereto the gears 905, 906 and 907 (see Fig. 46). Loosely journaled on shaft 902 and within a bearing 908 on the casing 903 is a sleeve 909 having fixed thereto within the casing a gear 910, and 20 external to said casing a wheel 911 having a flange 912 at its rim forming the outer member of a friction clutch. Slidably and rotatably carried by shaft 902 is a sleeve 913 having at one extremity thereof a wheel 25 914 having a friction clutch face mating the flange 912. At the other end sleeve 913 carries a belt pulley 915 which has fixed thereto a circular flange 916 forming the inner member of another friction clutch. 30 The outer member of this friction clutch is formed by the flanged wheel 917 fixed to or integral with the drum 918 journaled on shaft 902 and which also carries a belt pulley 919. Spring 911' is interposed be- 35 tween the members 911 and 914 to normally retain them out of frictional engagement and to retain the members 916 and 917 in frictional engagement. The outer end of the drum 918 is closed by means of a plate 920 adjacent the bearing 901. Fast to the shaft 902 and within the drum 918 is a 40 clutch disc 921 (see Fig. 50). Within recesses in the outer face of disc 921 are seated clutch elements 922 normally pro- 45 jecting outwardly into frictional contact with the inner face of the drum 918 by means of springs 923, this mechanism forming a one-direction clutch. Journaled within the casing 903 and parallel to shaft 902 50 is a second shaft 924 having a key 925 longitudinally set therein. Slidably mounted on shaft 924, but prevented from rotation by the key 925, is a sleeve 926 having fixed thereto gears 927, 928 and 929 arranged to 55 mesh selectively with the gears 905, 906 and 907, respectively, fixed to shaft 902, depending on the position of the sleeve 926 longitudinally of the shaft 924.

Fixed to shaft 924 at one end of sleeve 926 60 is a gear 930 which meshes continually with the gear 910 carried by the sleeve 909. A two-part collar 931 rotatably engages the sleeve 926, being seated in a suitable peripheral groove therein, whereby movement of

this collar longitudinally of shaft 924 serves 65 to slide sleeve 926 with its gears therealong. Collar 931 is provided with an arm 932 ar- 70 ranged to project through a slot 933 in cas- ing 903, and at its outer end this arm has a socket 934 in which is seated a plunger 935 75 urged toward the casing 903 by means of a spring 936. A button 937 is fixed to the outer end of plunger 935 by which it may be retracted against the action of spring 936. Perforations 938, 938^a, 938^b are provided in 80 the casing 903, in which the plunger 935 may extend to retain sleeve 926 in position when the gears 927, 928 and 929 are respec- 85 tively in position to engage the mating gears of shaft 904. A ring 940 is seated within a circumferential groove in the sleeve 913, and a yoke member 941 engages ring 940 at dia- 90 metrically opposite points by means of the pivot pins 942, 942^a, yoke 941 being in the form of a bell crank lever pivoted at 943 to a bracket 944 carried by the bracket 900 (see Figs. 45 and 48). Fixed to the vertical standard Y of the machine is a bracket 945 having journaled therein a shaft 946, this 95 shaft extending between a bearing 947 adja- 95 cent the standard Y and a bearing 948 spaced therefrom by means of a web 949. Fixed to shaft 946 is an arm 950, and piv- 100 otted at its lower end is a link 951 pivoted at its rear end to arm 952 of the bell crank 100 yoke member 941. Adjacent arm 950 is also fixed a second arm 953 to shaft 946, its lower end being bent outwardly from the standard Y and formed as a curved hook member 105 terminating in an inclined cam face 954. Carried by the web 949 is a vertical guide- 110 way 955 within which is slidably mounted a cam block 956, this cam block having a cam face 957 projecting therefrom in position to engage the cam face 954 of the arm 115 953. Loosely journaled on shaft 946 is a bell crank lever 958, the upper arm of which is pivotally connected to the rod 782 which, as before described, is connected to the ac- 120 tuating mechanism of the stop motion. The other arm of bell crank lever 958 projects within the vertical plane of the cam block 956, and terminates in a cam portion 959 somewhat above the cam portion 954 of the arm 953, and which will be engaged prior to the engagement of the latter on de- 125 pression of cam block 956. This cam block is pivoted to rod 960, which is pivoted at its lower end to an arm 961 fast to a rock shaft 962 journaled in the base of the machine, and carrying at its forward end a treadle lever 963. The arm 961 projects through a slot into the standard Y, and a spring 964 fast to the standard at one end and the end of arm 961 at the other end, serves to hold the treadle normally in raised position. A drive belt 965 passes over the pulley 919 and pulley 752 of the stop motion, while a second

belt 966 passes about the pulley 915 and a drive pulley 967 of any suitable power shaft, it being herein shown as the shaft of a motor 968 fastened to the machine base.

5 The operation of this mechanism is as follows:—When the treadle 963 is in raised position, pulley 915 is in frictional engagement with the pulley 919 through the frictional surfaces 916 and 917, the belt 966 thus 10 serving to drive pulley 915, and through the belt 965, the pulley 752 of the stop mechanism, this latter mechanism being in its stopped position with the pulley 752 out of engagement with the drum 740. On depression 15 of treadle 963 the rod 960 is depressed carrying with it cam block 956. The preliminary motion of this cam block acting against the surface 959 of the bell crank lever 958, serves to rock this bell crank lever 20 to depress rod 782. Depression of rod 782 serves to actuate the stop mechanism in the manner heretofore described to start the machine, the pulley 752 thereof being driven in the manner described through the belt 965, 25 pulley 919, pulley 915 and belt 966 from the motor or other source of power. Further depression of the rod 960, due to further depression of the treadle, brings the cam surface 957 of block 956 into engagement with the cam surface 954, which thereupon rocks 30 arm 953 outwardly, rocking the shaft 946 and arm 950, which, through the link 951, rocks the bell crank yoke member 952 to move the sleeve 913 into the position shown in Fig. 46, disconnecting the frictional engagement between members 916 and 917 and frictionally connecting members 914 and 911. Rotation of the pulley 915 will therefore now drive the member 911 rotating the sleeve 909 and the gear 910, which meshing with the gear 930, will rotate the shaft 924. In the position shown in Fig. 46, gear 927 40 carried by sleeve 926 is in mesh with the gear 905 fixed to shaft 902, whereby shaft 904 will be rotated at a speed ratio relative to that of the sleeve 909 corresponding to the relative sizes of the gears 930 and 905 to the gears 910 and 927. 45

Rotation of the shaft 902 is transmitted through the clutch disc 921 in a direction to urge the cam elements 922 to contact with the internal face of drum 918 to rotate the belt wheel 919, this rotation with the relative proportion of the gears shown being at a 50 slower speed than when the drive is direct from pulley 915 through the friction surfaces 916 and 917. Should the collar 926 have been moved to the right, as shown in Fig. 46, sufficiently for the plungers 935 to engage in the depressions 938^a or 938^b, the speed of the pulley 919 would have been reduced still further depending on the changed gear ratios between the meshing gears on shaft 924 and 902, it being clear 55 from the construction that this mechanism is a selective speed transmission of the sliding gear type. On allowing the treadle 963 to be raised through the action of spring 964, the cam block 956 will be raised out of contact with the arm 953, which thereupon 60 allows the spring 911' to disconnect the friction surfaces of members 911 and 914 thus throwing out the speed transmission and allowing the drive to be resumed through the friction surfaces 916 and 917 direct to the 65 pulley 919. It should be noted that the drum 918 is allowed to rotate with this arrangement of the friction surfaces without causing rotation of the shaft 902, the direction 70 of motion of the drum with relation to the clutch disc 921 at this time being such as to retract the clutch elements 922 out of locking contact with the drum 918. From the 75 above description, it may be seen that a preliminary depression of the treadle serves to 80 start the machine at its normal operative speed, while a further depression of the treadle thereafter serves to interpose a speed-change gearing to reduce the speed to any selected one of three speeds, each lower 85 than that of the normal speed, this construction being particularly designed to facilitate sewing about the toes of shoes, the higher of the reduced speeds being intended to be used when working around blunt toes, 90 and the lower speeds being intended for the more pointed shapes. While as shown, the speed transmission is utilized to reduce the speed, it might, if desired, be used to increase the speed by a proper proportion of 95 the gearing, the speed produced before the interposition of the transmission being the lower speed utilized for sewing about the toes, while the higher speed might be interposed by a further depression of the 100 treadle for sewing on the straight portions of the shoe. 105

It may be seen from the above description that all the sewing instrumentalities of this machine are actuated by a single shaft by means of three cam discs and one gear, the gear driving the shuttle and thread transfer mechanism, cam A driving the take-up; cam B driving the needle, looper, thread finger, and thread lock; and cam C driving the awl, 110 pull-off, thread measurer and presser foot. 115

Having thus described certain embodiments of my invention, though it is evident that many changes and modifications might be made therein without departing from its spirit or scope, what is claimed as new is,—

1. In a sewing machine, a circularly moving shuttle, and means for actuating said shuttle including a continuously rotating resilient power transmission element. 120

2. In a sewing machine, a rotary shuttle having a loop-taking hook, a drive mechanism therefor comprising a continuously rotating member having a pair of lugs arranged to engage within the shuttle hook, a 125

130

continuously rotating drive shaft, and driving connections including a spring between said shaft and said member through which spring the shuttle is driven.

5 3. In a sewing machine, a rotary shuttle, and a drive mechanism therefor comprising a continuously rotating member arranged to engage said shuttle, a continuously rotating drive shaft, a member carried on said drive 10 shaft, and a power transmitting spring carried by one of said members and engaging the other of said members.

4. In a sewing machine, a rotary shuttle, and a drive mechanism therefor comprising a continuously rotating member arranged to engage said shuttle, a continuously rotating drive shaft, a member carried on said drive 15 shaft, a power transmitting spring carried by one of said members and engaging the other of said members, and means to adjust 20 the tension of said spring.

5. In a sewing machine, a rotary shuttle, and a drive mechanism therefor comprising a continuously rotating member having a 25 socket and a pair of driving lugs to engage said shuttle, a continuously rotating drive shaft, a member carried thereby and having an element projecting adjacent said socket, and a power transmitting spring seated at 30 one end in said socket and bearing at its other end against said element.

6. In a sewing machine, a rotary shuttle, and a drive mechanism therefor, said mechanism comprising a member having on one 35 side thereof drive elements to engage said shuttle and on its opposite side an open-ended socket and the lug spaced from the open end of said socket, a drive shaft, a collar fixed to said shaft and having an 40 element projecting between said lug and said socket, a spring seated at one end in said socket and bearing against said projecting element, and a retaining plate carried by 45 said member for holding said collar in operative relation thereto.

7. A lock stitch sewing machine having, in combination, stitch forming mechanism comprising a hooked needle, a shuttle, a 50 bobbin carried in said shuttle, a thread transfer for removing the loop of thread from said needle, and a hook on said shuttle for removing the loop from said transfer and passing it about said bobbin, said thread transfer being constructed and timed to remove the thread-loop from the needle before 55 seizure of such loop by the shuttle.

8. A lock stitch sewing machine having, in combination, stitch forming mechanism comprising a curved hooked needle, a circularly moving loop-taker, a bobbin, and means for removing a loop of thread from 60 engagement with the needle and holding such loop spread unassisted by the needle in position for seizure by the loop-taker.

65 9. A lock stitch sewing machine having,

in combination, stitch forming mechanism comprising a hooked needle, a shuttle, a bobbin carried therein, a thread transfer constructed and timed to first remove the loop of thread from said needle and thereafter transfer such removed loop to the field of action of the shuttle, and a hook carried by said shuttle for removing the loop from said transfer and passing it about said bobbin. 75

10. A lock stitch sewing machine having, in combination, stitch forming mechanism comprising a hooked needle, a rotary shuttle having a thread hook thereon, a bobbin, and means for removing the loop of thread from 80 said needle and thereafter moving it bodily into the path of said shuttle hook whereby said shuttle hook removes the loop from said means and passes it about said bobbin. 85

11. A sewing machine comprising a plurality of sewing instrumentalities including a hooked needle, a shuttle provided with a loop taking hook, a bobbin in said shuttle, and a thread transfer member having a pair of spaced hook elements constructed and 90 arranged to remove the loop of thread from the needle and hold it in distended condition over said hook elements and thereafter transfer it into the path of said shuttle hook in position for said shuttle hook to pass between said hook elements to remove the loop therefrom and pass it about said bobbin. 95

12. A lock stitch sewing machine having, in combination, stitch forming mechanism 100 comprising a hooked needle, a multiple revolution shuttle having a thread hook thereon, a bobbin, and means for removing the loop of thread from said needle and thereafter moving it bodily into the path of said 105 shuttle hook for the shuttle hook to engage the loop, remove it from said means and pass it about the bobbin during one of its multiple revolutions.

13. A lock stitch sewing machine having, in combination, a main shaft, a shuttle, a shuttle drive for transmitting power from the main shaft to said shuttle, said shuttle drive having a multiple cycle of movement during each stitch forming operation, and 110 means actuated by said shuttle drive for presenting a loop of needle thread to said shuttle during one only of said cycles. 115

14. A lock stitch sewing machine having, in combination, a main shaft, a rotary shuttle, a shuttle drive for transmitting power from the main shaft to said shuttle, said shuttle drive rotating a plurality of times during each stitch forming operation, and means actuated by said drive for presenting a loop of needle thread to said shuttle during one rotation only thereof in each stitch forming operation. 120

15. A sewing machine comprising, in combination, a shuttle, a rotary actuating shaft 125

therefor, a cam shaft driven by said rotary shaft, a slidably mounted rock shaft, means actuated by said cam shaft to slide and rock said rock shaft, and a thread transfer carried by said rock shaft to present at suitable times a loop of needle thread to said shuttle.

16. A sewing machine comprising, in combination, a stitch forming instrumentality, a main shaft, a second shaft driven by said main shaft at a speed greater than said main shaft for actuating said instrumentality, a third shaft driven by said second shaft at a speed lower than said second shaft, and a second instrumentality co-operating with said first instrumentality and driven by said third shaft.

17. A sewing machine comprising, in combination, stitch forming mechanism including a needle, a loop taker, and a thread transfer for moving the loop of needle thread from the needle to the loop taker, a main shaft, a second shaft driven by said main shaft at a greater speed than said main shaft for actuating said loop taker, and a third shaft driven by said second shaft at a lower speed than said second shaft for actuating said transfer.

18. A sewing machine comprising, in combination, stitch forming mechanism including a needle, a loop taker, and a thread transfer for moving the loop of needle thread from the needle to the loop taker, a main shaft, a second shaft driven thereby and actuating said loop taker a plurality of times during each stitch forming cycle, and a third shaft driven by said second shaft and actuating said transfer once during each stitch forming cycle.

19. A sewing machine comprising, in combination, stitch forming instrumentalities including a needle, a shuttle having a loop taking hook, and a thread transfer for moving the loop of needle thread from the needle to the shuttle hook, a main shaft, a shuttle drive shaft driven by said main shaft at a higher speed than said main shaft, a cam shaft driven by said shuttle drive shaft at the same speed as said main shaft, and cams on said cam shaft for actuating said transfer.

20. A sewing machine comprising, in combination, stitch forming instrumentalities including a needle, a thread transfer for removing the loop of needle thread from said needle, a shuttle having a hook for taking the loop from said transfer, and means for actuating said instrumentalities in proper timed relationship, a yielding element being interposed in the shuttle actuating means to relieve strain on the thread as said shuttle hook takes the loop from said transfer.

21. A sewing machine comprising a plurality of driven loop-seizing instrumentalities, and operating mechanisms therefor,

and a casing constructed to retain certain of said instrumentalities and mechanisms in relative operative relationship whereby they may be inserted and removed from the machine as a unit.

22. A sewing machine comprising a plurality of sewing instrumentalities including a needle, a bobbin, a loop taker to pass a loop of needle thread about said bobbin, and a thread transfer to move the loop of needle thread from the needle into the path of said loop taker, and means holding said loop taker and transfer in operative relation as a unit whereby they may be assembled and disassembled together with relation to other portions of said machine.

23. A unitary structure comprising a plurality of driven needle-loop engaging instrumentalities of a sewing machine, and means for holding said instrumentalities in relative operative relationship, said structure being constructed and arranged to be assembled and disassembled as a unit with relation to other portions of the sewing machine.

24. In a sewing machine, sewing instrumentalities including a needle, an awl, a thread measurer, a thread lock, a looper, a thread finger, and a take-up, a cam for actuating said take-up, a cam for actuating said needle, looper, thread finger, and thread lock, and a cam for actuating said awl and thread measurer.

25. In a sewing machine, sewing instrumentalities including a needle, a looper, a thread finger, and a thread lock, and a single cam for actuating said needle, looper, thread finger, and thread lock.

26. In a sewing machine, a circularly moving shuttle having a loop-seizing beak and an opening adjacent said beak, a shuttle driving shaft, a shuttle driving element co-axial with but movable relative to said shaft and having a projection entering said opening, and a power-transmitting spring intermediate said shaft and shuttle driving element.

27. In a sewing machine, sewing instrumentalities including an awl, a tension, and a pull-off to supply slack thread to said tension, and a single cam for actuating said awl and pull-off.

28. In a sewing machine, sewing instrumentalities including a thread measurer, a tension, and a pull-off to supply slack thread to said tension, and a single cam for actuating said thread measurer and pull-off.

29. In a sewing machine, sewing instrumentalities including an awl, a thread measurer and a tension, and a single cam for actuating said awl and thread measurer.

30. In a sewing machine, a circularly moving shuttle having a loop-seizing beak and an opening adjacent said beak, a shuttle-driving shaft, a shuttle-driving element

coaxial with but movable relative to said shaft and having a projection entering said opening, an arm rigid with said driving shaft, and a spring intermediate said arm and shuttle-driving element.

31. In a sewing machine, sewing instrumentalities including a needle, a looper, a four-motion awl, a tension, and a pull-off

for supplying slack thread to said tension, a cam for actuating said needle and looper, 10 and a cam for actuating said awl and pull-off.

In testimony whereof, I have signed my name to this specification.

HENRY O. FLETCHER.
